UNITED STATES PATENT OFFICE.

LEONARD B. HARRIS, OF HADDON HEIGHTS, NEW JERSEY, ASSIGNOR TO HARRIS PATENTS COMPANY, OF NEW YORK, N. Y., A CORPORATION OF DELAWARE.

COMPRESSOR.

1,171,788.

Specification of Letters Patent. Patented Feb. 15, 1916.

Application filed July 15, 1914. Serial No. 851,070.

To all whom it may concern:

Be it known that I, LEONARD B. HARRIS, a subject of His Majesty King George of Great Britain, residing at Haddon Heights, in the county of Camden and State of New Jersey, have invented new and useful Improvements in Compressors, of which the following is a specification.

This invention relates to air compressors, and particularly to those types of air compressors which comprise a plurality of cylinders.

A principal object of the invention is to produce an air compressor of very simple and compact construction and arrangement of parts.

A further object of the invention is to provide an air compressor having an improved arrangement for cooling the air after compression, and having a construction particularly adapted for compressing the air in stages.

The invention is especially applicable to a type of compressor in which a pair of cylinders are disposed oppositely to each other in axial alignment, and one of the objects of the invention is to provide improved means for connecting and driving the air displacers or pistons from a common crank.

A further object of the invention is to provide means for producing a very simple and efficient construction for the parts associated with the high pressure cylinder where the invention is applied to a two stage compressor enabling these parts to be very compact and compactly arranged.

In all compressors, particularly those compressing air to a relatively high pressure, there is considerable loss in the cylinders due to clearance, and one of the objects of this invention is to provide an arrangement for reducing the loss from this clearance to a minimum.

A further object of the invention is to provide a simple arrangement for the cooling tubes which facilitates their insertion and removal from the compressor.

In the drawings, which illustrate a preferred form of my invention, Figure 1 is a plan, certain parts being omitted or broken away. Fig. 2 is a longitudinal vertical section through the compressor. Fig. 3 is an end view and partial section showing the high pressure end of the compressors.

Referring more particularly to the parts, the frame of the compressor preferably comprises a hollow base 10, the lower portion of which is of substantially rectangular form, and provided with suitable bosses 11 for holding down bolts to attach the base on a suitable foundation. The lower portion of this base is formed into a water chamber or reservoir 12, and end walls 13 of this water chamber are formed with openings 14 provided with removable cover plates 15. The end walls 13 are extended upwardly and unite with the upwardly extended side walls of the base to form a housing or crank case 16, said housing having an enlarged central opening 17, which is closed normally by a removable saddle plate or bonnet plate 18. This upper portion of the base forms a crank chamber, and is provided on opposite sides with suitable bearings 19 for a crank shaft 29, the axis of which is preferably disposed on the central transverse axis of the base. The bearings 19 are provided with suitable removable caps 20. In the present embodiment of the invention the cylinders 20 are separate from the base but are supported entirely by the base. Above the end cover plates 15 the base is formed with end faces 21 and 22, the latter of which in the present instance forms a seat for a low pressure cylinder 23 provided with a suitable flange for this purpose. The cylinder is open at its inner end, and provided with a displacer 24, preferably in the form of a trunk piston having suitable packing rings 25 near its outer end, and provided with a wrist pin 26 to which a connecting rod 27 is attached, the opposite end of the said connecting rod being attached to the crank 28 on the aforesaid crank shaft 29. The outer portion of the cylinder 23 is formed with a water jacket 30, and this water jacket is preferably connected by a pipe connection 31 with the upper portion of the water chamber at the point 32. A suitable oiling connection 33 is provided for lubricating the displacer or piston 24.

The outer end of the cylinder 23 is provided with an air head 34 of any common form provided with an inlet valve 35, which may take air from the atmosphere, said valve comprising a suitable substantially tubular case 36 and a poppet valve 37 seating at the inner end of the valve case and provided with a spring 38 around its stem 39.

for facilitating the seating of the valve in the compressing movement of a displacer or piston 24. Preferably, in the lower part of the head, I provide an outlet valve 40 presenting a seat 41 for the valve plunger 42, said plunger being held on said seat normally by a spring 43, held in place by the removable bonnet 44.

In order to cool the air after it comes from the cylinder 23, I prefer to pass it through cooling pipes or coils 45 in the water chamber 12. Where the compressor is of a two stage type this cooling chamber constitutes an intercooler for cooling the air between the stages of compression, and if desired it may also be used as an after-cooler to cool the air after its final compression. This is the arrangement illustrated, that is I provide a cooling pipe or coil 45 which takes the air from the low pressure cylinder, and which delivers it to the high pressure cylinder. I also provide a similar coil 46, which takes the air from the high pressure cylinder and cools it, and then delivers it to the service pipe. These coils 45 and 46 are preferably elongated longitudinally of the longitudinal axis of the air compressor. The coil 45 has a straight extension 47 which passes through a stuffing box 48 in the cover plate 15, which is adjacent to the low pressure cylinder, and a suitable connection or coupling 49 is made with the projecting extremity of this extension. A suitable pipe connection 50 leads to the coupling from a similar coupling 51, which connects with the air head 34, so as to conduct the air into the coil. The other end of the coil 45 is provided with a straight extension 52 which passes through a similar stuffing box 53 in the cover plate 15, which is adjacent to the high pressure cylinder 54.

The arrangement and construction of the high pressure cylinder and its associated parts will now be described. Instead of bolting the high pressure cylinder directly to the base I prefer to provide a high pressure cylinder seat 54 having a flange 55 which is attached to the end face 21. This seat, as indicated most clearly in Fig. 2, is offset away from the crank shaft 29, and is provided with an enlarged opening or counterbore 55', which receives a center plate 56, upon which the inner end or head 57 of the high pressure cylinder 54' seats. In order to make an efficient packing for the high pressure piston 58 at this point I prefer to provide the inner end of the high pressure cylinder with a circumferential recess 59 in which I provide a cup leather 60, said cup leather being held between the center plate 56 and the head of the cylinder in the recess 59. The inner portion of the seat 54 is formed with an integral cross head guide 61, at one end of the guide and the unsupported end of the guide projects toward the

shaft 29, said cross head guide comprising an upper guide 62 and a lower guide 63, between which a cross head 64 is arranged to reciprocate. Said cross head is formed with oppositely projecting pins 65, and to these pins attach connecting rods 66, the cross head ends of these rods being held in position by suitable washers 67 and pins 68. These rods 65 attach to the same crank 28 that the rod 27 attaches to, the heads 69 of the rods 66 being disposed on opposite sides of the head 70 of the rod 27, and in this way taking up the length of the crank pin 28. With this arrangement it is understood that I provide a pair of connecting rods for the high pressure end which are disposed respectively on opposite sides of the cross head guide. This arrangement is very advantageous as it produces a very compact arrangement of parts. A suitable oil gutter 71 is formed in the upper side of the cross head which passes under an oil connection 72 which keeps the cross head properly lubricated. The outer end of the high pressure cylinder is provided with a suitable air head 72', which is provided with a suitable inlet valve 73 consisting of a poppet 74, which is normally held on its seat by suitable spring 75 arranged upon the stem of the valve. The case of this valve 73 is of tubular form, and is connected to an elbow 76, which elbow is in turn connected by a pipe connection 77 with the extension 52 from the intercooler. Suitable couplings 78 and 79, are used for making the connections, and the pipe connection is also preferably provided with a suitable relief valve 80 of any suitable construction. The outlet valve 81 for the high pressure cylinder is of the same type as the outlet valve 41 of the low pressure cylinder, but of smaller dimensions, and, furthermore, the outer portion of the high pressure valve 81 is provided with a threaded nipple 82 for making a connection with a pipe indicated at 83, which leads the air from the high pressure cylinder down into the coils 46 of the after cooler.

In connection with the high pressure piston I provide an arrangement for insuring that the clearance in the end of the cylinder will be reduced to a minimum. For this purpose I prefer to form the high pressure piston 84 of substantially tubular form, and arrange it with its inner end abutting against a counterbore 85 in the outer face of the cross head. I then secure this tubular piston to the cross head by means of a through bolt or stem 85', the outer end of which is formed with a head 86, seating on the outer end of the tubular piston 84, and preferably forming an extension of the same, said head being of the proper diameter to fit neatly in the bore of the cylinder. This head 86 retains the packing rings 87 of the piston. In order to insure that in the

outward stroke of the piston this head will travel just exactly to the end of the bore of the cylinder, I prefer to provide under the head 86 a washer 88 of a predetermined thickness. The stem of the bolt 85 projects through the inner face of the cross head, that is the face of the cross head, which is adjacent to the crank case, and this projecting end is preferably provided with adjusting nuts 89, by means of which the head 86 of the bolt can be drawn up securely against the washer. Attention is called to the fact that the means for adjusting this head 86 is readily accessible. The high pressure cylinder 54' is preferably provided with a water jacket 90 of cylindrical form and provided with flange 91, which seats over and bolts to the flange 55 of the high pressure cylinder seat. A suitable oil connection 92 is made through the jacket 90 connecting with drilled holes 93 for conducting oil down to the high pressure piston or high pressure air displacer.

The water jacket 90 is connected by a suitable pipe connection 94 with the water chamber 12, said connection having its ends attached at the points 95 and 96. The outer end of the jacket 90 is provided with a water outlet 97 and has an integral outer head with an opening 98, which receives the outer end of the air head 72. The said outer end of the air head 72 projects through this opening, and is preferably threaded so as to receive a nut 99, which clamps down on the head of the jacket and secures the same in position. The pipe, which is indicated at 83 for conducting the air from the high pressure cylinder to the cooler preferably has connected with it a relief valve indicated in dotted lines at 100 in Fig. 3, said relief valve being of any suitable construction.

Special attention is called to the arrangement of the cross head guide between the pair of connecting rods which connect the cross head with the crank, and also to the use of this arrangement in combination with a trunk piston for the low pressure cylinder. This arrangement together with the offset of the seat for the high pressure cylinder, enables me to bring the axis of the crank shaft on the central transverse axis of the base. Special attention is also called to the arrangement of the after cooler and inter-cooler in the base of the compressor, and also to the advantageous arrangement for facilitating the arrangement or removal of the cooling coils. This is evidently accomplished simply by disconnecting the couplings 49 and 79, and then removing the cover plates 15.

It is evident that the bottom, end walls and upper wall 12^a of the base form retaining walls for confining water within the base so that the base constitutes a relatively large reservoir for the cooling water. This

is very advantageous as it tends to prevent extreme or sudden changes in the temperature in the air connections and this is very desirable. Securing the cylinders and the covers of the reservoir on the end walls of the base is considered highly advantageous as it very much simplifies the finishing of the parts and facilitates the assembling of the parts. Special attention is called also to the construction and arrangement of the high pressure piston for adjusting the piston to prevent losses due to clearance at the end of the cylinder, and the method of putting on or removing the packing rings without "springing" them made possible by this arrangement.

It is understood that the construction described above is only one of the many embodiments or forms my invention may take, and I do not wish to be limited in the practice of the invention, nor in my claims, to the particular embodiment set forth.

What I claim is:

1. An air compressor, comprising, in combination, a hollow base, an air cylinder at one side of said base separate from said base and supported entirely by said base, a second air cylinder separate from said base and supported entirely by said base at the other side of said base and opposite said first cylinder, a crank shaft disposed between said cylinders, the bottom, end walls and the upper wall of said base operating to confine water whereby said hollow base constitutes a reservoir, air displacers reciprocating in said cylinders and connected with said crank shaft, and air cooling coils in said reservoir connected with said cylinders.

2. An air compressor, comprising, in combination, a hollow base, an air cylinder at one side of said base separate from said base and supported entirely by said base, a second air cylinder separate from said base and supported entirely by said base at the other side of said base and opposite said first cylinder, a crank shaft disposed between said cylinders, the bottom, end walls and the upper wall of said base operating to confine water whereby said hollow base constitutes a reservoir, air displacers reciprocating in said cylinders and connected with said crank shaft, and air cooling coils in said reservoir connected with said cylinders, said base having a crank case inclosing said crank shaft, the upper wall of said base forming the bottom wall of said crank case.

3. An air compressor, comprising, in combination, a hollow base having a bottom wall, end walls and an upper wall, an air cylinder separate from said base seating upon and supported entirely on one of said end walls, a second air cylinder separate from said base seating upon and supported entirely on the other end wall of said base opposite said first cylinder, a crank shaft

disposed between said cylinders, the said bottom, end wall and upper wall of said base operating to confine water whereby said hollow base constitutes a reservoir, removable covers for said reservoir seating on said end walls, pistons reciprocating in said cylinders and connected with said crank shaft, and air cooling coils within said reservoir connected respectively with said cylinders.

4. An air compressor, comprising, in combination, a hollow base, an air cylinder separate from said base and entirely supported on said base at one side, a second air cylinder separate from said base and entirely supported on said base at the other side and opposite to said first cylinder, a crank shaft disposed between said cylinders and having a crank pin, pistons reciprocating in said cylinders, a connecting rod connecting said crank pin with one of said pistons, a cross-head guide for the other cylinder projecting toward said crank shaft, a crosshead moving in said crosshead guide and connected with the adjacent piston, a connecting rod on each side of said guide attached to said crosshead and attached to said crank pin, said base having a bottom, end walls and an upper wall for retaining water whereby said base constitutes a reservoir, said base having a crank case thereabove, the upper wall of said base forming the bottom wall of said crank case, and air cooling coils in said reservoir connected respectively with said cylinders.

5. An air compressor, comprising, in combination, a base having a water chamber, an air cylinder mounted on said base at one side, a second air cylinder mounted on said base opposite said first cylinder, a pair of cooling coils in said water chamber, means for connecting both of said cylinders with one of said cooling coils adjacent said cylinders, means for connecting the other coil with one of said cylinders, said water chamber having removable covers adjacent said cylinders, said cooling coils having integral extensions passing through said covers, the connection with said cylinders being formed on the exterior of said covers, and stuffing boxes in said covers where said coil extensions pass through the same.

6. An air compressor comprising in combination, a base having a water chamber, an air cylinder mounted on said base at one side, a second air cylinder mounted on said base opposite said first cylinder, cooling pipes in said water chamber, means for connecting said cylinders with said cooling pipes adjacent said cylinders, said water chamber having removable covers adjacent said cylinders, said cooling pipes being in the form of coils elongated longitudinally of the axes of said cylinders and having integral extensions passing through said

covers, and stuffing boxes in said covers where said extensions pass through the same.

7. In an air compressor in combination, a base, a low pressure cylinder supported on said base at one side, a high pressure cylinder supported on said base opposite said first cylinder, a crank shaft having a crank disposed between said cylinders, a trunk piston reciprocating in said low pressure cylinder, a connecting rod connecting the same with said crank, a cross head guide adjacent said high pressure cylinder, and extending toward said crank shaft, a cross head reciprocating in said guide, a high pressure piston connected therewith and reciprocating in said high pressure cylinder, and a pair of connecting rods connecting said crank with said cross head, and lying respectively on the opposite sides of said cross head guide.

8. In an air compressor, in combination, a base, a low pressure air cylinder supported on said base, a trunk piston reciprocating therein, a high pressure air cylinder supported on said base opposite said first cylinder, a crank shaft disposed between said cylinders over said base, a crosshead guide projecting from said high pressure cylinder toward said crank shaft, a high pressure piston reciprocating in said high pressure cylinder, a crosshead connected therewith sliding on said guide, a pair of connecting rods attached to said crosshead guide and disposed on opposite sides of said crosshead, and a connecting rod attached to 100 said trunk piston, said crank shaft having a common pin attached to all three of said connecting rods.

9. In an air compressor, in combination, a base, an air cylinder supported on said base at one side, a second air cylinder supported on said base at the other side, a crank shaft disposed between said cylinders, a piston reciprocating in said first named cylinder, a piston reciprocating in 110 said second named cylinder, a crosshead guide corresponding to said second named cylinder and projecting therefrom toward said crank shaft, a crosshead sliding in said guide and attached to the piston of said second named cylinder, a pair of connecting rods attached to said crosshead respectively on opposite sides of said guide, and a connecting rod attached to said first named piston, said crank shaft having a common 120 crank pin attached to all of said connecting rods, said crosshead supported entirely from its outer end adjacent its corresponding cylinder.

10. In an air compressor in combination, a base, a low pressure air cylinder mounted on said base at one side, a high pressure air cylinder mounted on said base opposite said first cylinder, a piston reciprocating in said low pressure cylinder, a high pressure pis- 130

- ton reciprocating in said high pressure cylinder, a seat having an opening therethrough, through which said high pressure piston passes, means for attaching the end 5 of said high pressure cylinder to said seat, a cross head guide formed integral at one end with said seat, the other end of said cross-head guide being unsupported and projecting toward said low pressure 10 cylinder, a cross head reciprocating on said cross head guide, and connected with said high pressure piston, a crank shaft having a crank between said cylinders, a connecting rod connecting said crank with said low 15 pressure piston, a pair of connecting rods connecting said crank with said cross head and disposed respectively on opposite sides of said cross head guide.
11. In an air compressor in combination, 20 a base, a low pressure air cylinder bolted to an end face of said base, a seat for a high pressure air cylinder bolted to the opposite end face of said base, a high pressure air cylinder bolted to said seat, a low pressure piston reciprocating in said low pressure cylinder, a high pressure piston reciprocating in said high pressure cylinder, said seat 25 being offset away from said end face toward said high pressure cylinder, a cross head guide formed integral with said seat and projecting away from said high pressure cylinder, a cross head reciprocating in 30 said cross head guide and connected with said high pressure piston, a crank shaft disposed substantially on the central axis of said base and having a crank between said cylinders, a connecting rod connecting said crank with said low pressure cylinder, a pair of connecting rods connecting said crank with said cross head and disposed respectively on opposite sides of said cross head, and a water jacket for said high pressure cylinder bolted over said seat. 35
